US00D570335S

(12) **United States Design Patent** (10) **Patent No.:** **US D570,335 S**
(45) **Date of Patent:** **** Jun. 3, 2008**

(54) **DOCK INSERT**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, San Francisco, CA (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, deceased, late of Palo Alto CA (US); by **Vincent Keane Seid**, legal representative, Los Gatos, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/281,495**

(22) Filed: **Jun. 25, 2007**

(51) LOC (8) Cl. **14-02**

(52) U.S. Cl. **D14/217**

(58) Field of Classification Search **D14/142, D14/149, 217, 251, 432, 434, 435, 447, 496; D13/107, 108, 118; 248/221.11, 309.1; 320/107, 320/110, 113-115; 361/600, 679, 683, 686; 439/529, 534; 455/556.1, 556.2, 557**

CLAIM

The ornamental design of a dock insert, substantially as shown and described.

DESCRIPTION

FIG. 1 is a front perspective view of a dock insert showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another front perspective view thereof showing the design in combination with an environment in which the design may be used; and,

FIG. 9 is another perspective view thereof.

The broken lines in the Figures are for illustrative purposes only and form no part of the claimed design.

1 Claim, 5 Drawing Sheets
